R. A. WAITELING.
FLAG HOLDER.
APPLICATION FILED AUG. 2, 1917.

Patented Apr. 16, 1918.

INVENTOR

ROYAL A. WAITELING.

BY

Herbert H. Thompson
ATTORNEY.

UNITED STATES PATENT OFFICE.

ROYAL AGUSTUS WAITELING, OF PITTSFIELD, MASSACHUSETTS.

FLAG-HOLDER.

1,262,879.

Specification of Letters Patent. Patented Apr. 16, 1918.

Application filed August 2, 1917. Serial No. 184,023.

To all whom it may concern:

Be it known that I, ROYAL AGUSTUS WAITELING, a citizen of the United States of America, residing at 203 Woodlawn avenue, Pittsfield, in the county of Berkshire and State of Massachusetts, have invented certain new and useful Improvements in Flag-Holders, of which the following is a specification.

10 The principal objects of this invention are to devise a holder for small flags, banners, pennants or the like which may be manufactured at small cost and may be readily attached and made ready for use. My invention is especially adapted for use in securing small flags to the wind shields or other parts of automobiles.

Referring to the drawings in which what I now consider the preferred forms of my invention are shown:

Figure 1 is a plan view of one form of my invention.

Fig. 2 is a diagrammatic perspective view of a portion of the wind shield of an automobile, showing one method of attaching the holder.

Fig. 3 is a perspective view showing how my holder may be used on a flat surface, such as the window sill of a dwelling.

30 Fig. 4 is a section on line 4—4 of Fig. 1. The flag holder comprises a base plate or strip 1 of metal. Preferably said plate is made of malleable iron or brass so that it may be readily bent by the user to cause the shank portion 2 to assume any desired angle to the foot 3 (see Fig. 3 for instance). The foot of said plate is provided with suitable means, such as an aperture 4 for securing it to a support, such as the wind shield 5 of an automobile. All that need be done to so attach the holder is to remove the usual adjusting nut or bolt 6 on the wind shield, place the plate in position and replace the nut or bolt (see Fig. 2).

45 On said plate, I provide ears 7, 8, formed preferably integrally with the plate. Each of said ears is turned and tightly clamped over a longitudinally extending member 9 of resilient wire or the like. Said members, together with the transversely extending portions 10 adjacent either end, form a resilient, but strong clip 20, adapted to hold a flag staff 11 or the like between it and the base plate. The end portions 10 may be provided with a hump 12 to fit over the staff and hold the same firmly in position. Ears 7 and 8

are located preferably near the middle of members 9 so that a maximum, equal pressure is exerted at the two spaced points 12 on the staff. Also, clip 20 preferably extends the greater portion of the length of shank 2, securing a long base line of support for the staff. It will be readily apparent that my invention is adapted to hold many different sizes of flag staffs, as clip 20 is sufficiently long and flexible to accommodate various sizes of staffs. The foot 3 may also have holes 13 therein for securing it by screws 14 to a flat support 15 such as a window sill of a dwelling or the like. When used in this manner the shank 2 may be bent upwardly at or near point 16 as explained hereinbefore, so that the flag 11 is held out at the desired angle.

In accordance with the provisions of the patent statutes, I have herein described the principle of operation of my invention, together with the apparatus, which I now consider to represent the best embodiment thereof, but I desire to have it understood that the apparatus shown is only illustrative and that the invention can be carried out by other means. Also, while it is designed to use the various features and elements in the combination and relations described, some of these may be altered and others omitted without interfering with the more general results outlined, and the invention extends to such use.

Having described my invention, what I claim and desire to secure by Letters Patent is:

1. A staff holder comprising a base plate, having an aperture therein adapted to be used in securing it to a support, ears on said plate, and a resilient wire member secured to said plate by said ears adapted to clamp a staff between said member and said plate. 95

2. As an article of manufacture, a staff holder comprising a base plate, integrally turned over ears thereon and a resilient member having longitudinally extending portions, said portions being embraced by said ears and a transverse portion adapted to clamp the staff to said plate. 100

3. A staff holder comprising a substantially rectangular base plate, a wire clip having longitudinal members and a transverse member adjacent each end and means for securing each of said longitudinal members to said plate at an intermediate point thereof. 110

4. A staff holder comprising a substantially rectangular base plate, a wire clip having longitudinal members and a transverse member adjacent each end, and means for securing each of said longitudinal members to said plate at an intermediate point thereof, said transverse members having humps therein adapted to fit the staff.

5. As an article of manufacture, a staff

holder comprising a base plate, integrally turned over ears thereon, a resilient member having longitudinally extending portions, said portions being embraced by said ears, and transverse portions adapted to engage the top of the staff.

15

In testimony whereof I have affixed my signature.

ROYAL AGUSTUS WAITELING.
